UNITED STATES PATENT OFFICE

JOHN E. EUTH, OF CHICAGO, ILLINOIS, ASSIGNOR TO UNITED AUTOGRAPHIC REGISTER CO., OF CHICAGO, ILLINOIS, A CORPORATION OF ILLINOIS

DUPLICATING MACHINE

Original application filed September 9, 1929, Serial No. 391,207. Divided and this application filed February 2, 1931. Serial No. 518,041.

This invention relates particularly to duplicating machines of the type in which the paper webs are carried over a flat platen mounted between rails which support a typewriting machine, which co-operates with the platen.

The primary object is to provide improved mechanism adapted to sever paper webs which have been drawn over the platen.

10 The present application constitutes a division of my application Serial No. 391,207, filed September 9, 1929.

The invention is illustrated in a preferred embodiment in the accompanying drawings, 15 in which—

Figure 1 is a side elevational view of a duplicating machine embodying the invention; Fig. 2, a broken plan view of the platen and cutting mechanism; Fig. 3, a broken 20 longitudinal vertical sectional view taken as indicated at line 3 of Fig. 2; Fig. 4, a similar view showing the blade after it has severed the webs, taken as indicated at line 25 4 of Fig. 2; and Fig. 5, a perspective view 25 on an enlarged scale showing the cutting blade.

In the preferred embodiment illustrated, A designates a frame comprising a standard A' and a surmounting horizontally disposed 30 bed A²; B, a platen mounted in the front portion of the bed; C, a typewriting machine on rails which form the main portion of the bed; D, web-control-mechanism mounted in the rear portion of the bed A²; and E, web- 35 cutting mechanism mounted on the front portion of the bed A².

The duplicating machine comprising the frame A and the typewriter C mounted thereon are of well-known construction. The 40 typewriter is mounted on longitudinal rails 1, having rearward extensions, or arms, 1^a between which the demountable device D is supported. As shown in Figs. 3 and 4, the rails or longitudinal members are connected 45 at their front ends by a cross-bar 2, which is equipped with pins or hooks 3 adapted to engage register perforations with which the multiple strips of paper are provided.

The platen B is mounted in a manner usual 50 in this type of machine. It is normally held

in the raised position by mechanism 4 actuated by a spring 5. Mechanism 4 is equipped with a lever 6 which is connected by a link 7 to a treadle or foot-lever 8 which is supported on a pivot 9 carried by fixed arms 10 which project from a cross-bar or rod 11, which connects the members of the standard A' near their lower ends.

The mechanism 4 also includes a rock-shaft 12 having fixedly secured thereto bent arms 13 which are connected at their free ends by a clamping-bar 14 which constitutes also one of a pair of shear-members. The bar 14 is provided with perforations 14^a which accommodate the hooks 3 when the bar is in clamping position.

The typewriter C is capable of being moved forwardly and rearwardly on the track for line-spacing, and is capable of being fed transversely in the typing operation.

The web-control mechanism D is described in detail in my co-pending application Serial No. 391,207.

The cutter mechanism E comprises a rotatable shear-member 15 which co-acts with the shear-member 14. The shear-member 15 is provided with trunnions 16 which are journaled in bearings 17 with which the front ends of the member 1 are equipped. An operating handle 18 is provided to rock the shear-member 15 and is held upright normally by a spring 19 which is kept in position by an arcuate arm 20 passing through the coil of the spring. The shear-member 15 has a shearing-edge 15^a which, preferably, has a high point at the center and tapers in both directions therefrom, so that when the paper is sheared it is first pierced at the center and then sheared in both directions therefrom.

The foregoing detailed description has been given for clearness of understanding only, and no unnecessary limitations should be understood therefrom, but the appended claims should be construed as broadly as 90 permissible, in view of the prior art.

What I regard as new, and desire to secure by Letters Patent, is:

1. In combination: a frame having arms between which a platen is mounted; clamp- 100

ing means mounted on said frame in front of the platen and adapted to grip webs led over said platen; and a rotatable shear-member adapted to co-act with said clamping means to sever webs held by the clamping means.

2. In combination: a frame provided with web-supporting means; a spring-held clamping-member provided with a shearing edge, adapted to grip webs downwardly against said web-supporting means; and a rocking shear-member journaled in said frame and adapted to rock upwardly in shearing relation to said clamping-member so as to co-act with said clamping-member and sever webs gripped thereby.

JOHN E. EUTH.
